Primary Examiner — Kevin K Rudzinski*Assistant Examiner* — Richard E Yenchesky(74) *Attorney, Agent, or Firm* — Howard Russell(57) **CLAIM**

I claim the ornamental design for a hinged dust hood, as shown and described.

DESCRIPTION

FIG. 1 is a bottom left-side perspective view of a hinged dust hood showing my new design;

FIG. 2 is a top rear right-side perspective view thereof;

FIG. 3 is a bottom view thereof;

FIG. 4 is a right-side view thereof;

FIG. 5 is a top view thereof;

FIG. 6 is a left-side view thereof;

FIG. 7 is a front view thereof;

FIG. 8 is a rear view thereof;

FIG. 9 is a bottom front left-side perspective view in an open position thereof; and,

FIG. 10 is a top front right-side perspective view in an open position thereof.

The broken lines in FIG. 4 represent boundaries that form no part of the claimed design.
